(57) **CLAIM**

The ornamental design for a stand for electronic device, as shown and described.

DESCRIPTION

FIG. 1 is a front, top and left perspective view of stand for electronic device showing claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a back, bottom and right perspective view thereof; and,

FIG. 9 is a front, top and left perspective view thereof in use. The broken lines depict environment and form no part of the claimed design.

1 Claim, 8 Drawing Sheets(56)
